The ornamental design for a lighting device bezel, as shown and described.

DESCRIPTION

FIG. 1 is a first front perspective view of a lighting device bezel showing our new design, implemented as part of an example lighting device.

FIG. 2 is a front perspective view of the lighting device bezel. FIG. 3 is a cross-sectional view through the lighting device bezel, as seen along the lines of the section 3-3 taken in FIG. 2.

FIG. 4 is an enlarged view of a portion 4 of the lighting device bezel identified in FIG. 3.

FIG. 5 is a second front perspective view of the lighting device bezel, implemented as part of the example lighting device of FIG. 1.

FIG. 6 is an enlarged view of a portion 6 of the lighting device bezel identified in FIG. 5.

FIG. 7 is a front side elevational view of the lighting device bezel.

FIG. 8 is a top plan view of the lighting device bezel.

FIG. 9 is a bottom plan view of the lighting device bezel.

FIG. 10 is a left side elevational view of the lighting device bezel; and,

FIG. 11 is a right side elevational view of the lighting device bezel.

The broken lines in the drawings illustrate environmental features and form no part of the claimed design.
